UNITED STATES PATENT OFFICE.

ANTONIO A. SILVA, OF BOSTON, MASSACHUSETTS.

PLATFORM ATTACHMENT FOR LADDERS.

Application filed February 20, 1928. Serial No. 255,597.

The invention relates to a new and useful improvement in separable platform device for attachment to a ladder.

The object of the invention is to provide a platform device which may be attached to the rounds of a ladder on which the workman can stand while painting or doing other work on the wall of a building and which may be moved from one round of the ladder to another according to the elevation desired by the workman. Another object of the invention is to adapt the device for ladders of different widths.

Referring to the drawings,

Fig. 1 is a front elevation of a ladder standing in an inclined position against a wall and having the device attached thereto.

Fig. 2 is a vertical section on line 2—2 of Fig. 1.

Fig. 3 is a plan view of Fig. 1.

Fig. 4 is a perspective view showing the device attached to a ladder in position for use.

Fig. 5 is a perspective view of the platform device embodying the invention detached from the ladder and in collapsed form.

Fig. 6 shows in full lines the platform device adjusted to a ladder of less width, and showing in dotted lines how it is adjusted to a ladder of greater width than that shown in Fig. 1.

In the drawings there is shown at 10 a platform on which the workman is to stand while doing his work and having connected therewith the means for attaching it to the rounds of the ladder.

Secured to the rear side of the platform 10 are two pairs of hooks 11—11, 12—12, the hooks 11 being adapted to engage over the upper side of any one of the rounds such as 13 of the ladder and the weight of the platform will press the hook 11 down on the round and sustain the weight. The hook 12 is normally spaced a little below the round 13 but is adapted to engage with the under side of the round if the platform is moved up slightly and is for the purpose of preventing the platform from becoming disengaged by slipping upwards. Secured to the front part of the platform are a pair of short angle bars 14—14, each having a horizontal arm 14^a and a vertical arm 14^b. The horizontal arm 14^a extends beneath the platform and has a swivel connection therewith by a pivot bolt 9. Said arm 14^a extends outward toward the front slightly beyond the front edge of the platform and affords clearance between the upright arm 14^b and the edge of the platform so that the said angle bar is capable of a slight swiveling movement on the vertical axis of the pivot 9. This also permits the upright arm 14^b to swivel with the horizontal arm.

Two brace bars 15—15 are each hinged at one end as shown at 16 to the upwardly extending branch 14^b of the angle bar 14, said bar 15 being inclined upwardly and rearwardly with relation to the upwardly extending bar 14 and at its upper end it is provided with a hook 17 which is adapted to engage over the round 19 next above the round 13. It is also provided with a hook 18 a short distance below the hook 17 which is adapted to engage over the round 19 if the distance between rounds 13—19 is less than the distance adapted for the use of the hook 17. The hook 18 may also be employed even when the rounds are the same distance apart. This provision of two sets of hooks 17, 18 allows the ladder to be set at varying angles of inclination and still maintain the platform in a substantially horizontal plane. There is a very little play between the front edge of the platform and the upwardly extending arm of the angle iron 14 so as to allow a slight swivelling movement of said arm. The pivot connection 16 between the bar 15 and the said upright member of the angle bar 14 allows the upper ends of the brace bars 15 to be turned toward each other to accommodate them to a ladder in which the side rails 20 are more narrowly spaced or more widely spaced apart from each other. It will thus be seen that the platform is adapted to be mounted on the ladder in connection with any two adjacent rounds to vary the height of the platform from the ground or floor. Also it is adapted for attachment to ladders of different widths as it is preferable to have the hook connections with the ladder come just inside of the side rails. It can be readily shifted from one position to another. For instance, if the workman desires after finishing his work while standing on the platform as shown in Fig. 1, he can step onto the round below and then easily move the platform down one round, then step back onto the platform without having to go down to the ground or floor and take down the ladder to make the shift.

The platform is long enough to extend beyond the side rails 20 of the ladder. The braces 15—15 are between the side rails 20 but are spaced apart far enough for the 5 workman to stand between them. As the said braces are upwardly inclined they serve as side guards for the workman to keep him from accidentally stepping off from the end of the platform.

10 What I claim is:

1. A separable platform attachment for a ladder comprising a platform, hooks attached to the rear part of the platform and adapted to engage with one of the rounds of 15 a ladder, two supporting rods each having at one end a swivel connection with the front part of the platform, said rods extending upwardly and rearwardly from said connection, the upper ends being free to move toward 20 and from each other to vary the distance between them, each of said rods having at its upper end means for connecting it with one of the rounds of the ladder above the rear edge of the platform.
- 25 2. A separable platform attachment for a ladder comprising a platform, hooks attached to the rear part of the platform and spaced apart from each other, said hooks being adapted to engage over one of the 30 rounds of a ladder, two angle bars each of which has a horizontal arm and a vertical

arm, the horizontal arm being pivotally connected with the front part of said platform whereby said horizontal arms may be swivelled and the upright arms moved therewith, 35 two supporting rods, each connected at its lower end with the upright portion of said angle bar by a swivel joint, the upper ends being free to move toward and away from each other, the upper ends of said rods each 40 being provided with means to engage one of the rounds of the ladder at a higher elevation than the round with which the platform hooks are engaged.

3. A separable platform attachment for 45 a ladder comprising a platform, hooks attached to the rear part of the platform and adapted to engage with one of the rounds of a ladder, two supporting rods each having at its lower end a swivel connection with 50 the front part of the platform whereby they may be turned to vary the distance between their upper ends, said rods extending upwardly and rearwardly, each of said rods having at its upper end means for connect- 55 ing it with one of the rounds of the ladder above the rear edge of the platform, said platform being of a substantially greater length than the distance between the said supporting rods.

In testimony whereof I affix my signature.
ANTONIO A. SILVA.
